U. S. PATENT OFFICE.

No. 77.

1861.

WHOLE No. 1,442.

Plates of a Cooking Stove.

JAMES HORTON AND JOHN MARTINO, OF PHILADELPHIA, PA.,
ASSIGNORS TO DAVID STEWART AND RICHARD PETERSON, OF SAME PLACE.

Letters Patent for a Design No. 77, dated July 16, 1861.

SPECIFICATION.

TO ALL WHOM IT MAY CONCERN:

Be it known, that we, JAMES HORTON and JOHN MARTINO, both of the city of Philadelphia, county of Philadelphia, State of Pennsylvania, have invented or produced a new and original design for Plates of a Cooking Stove, termed the United States; and we do hereby declare the accompanying drawing, with the following explanation of the same, to form a full, clear, and exact description of said design.

Fig. 1 of the drawing represents one of the side plates.

Fig. 2, the lower front plate.

Fig. 3, the upper front plate; and

Fig. 4, the back plate of the stove.

The said plate, fig. 1, of the stove, is edged with a plain moulding, and has an oven door A and panel B, the former being edged with a moulding, partly plain and partly denticulated, and enclosing a scrolled and foliated ornament.

The panel B is edged with a moulding similar to that of the oven door, and encloses the scrolled and foliated ornament seen in the drawing.

The lower front plate, fig. 2, of the stove, has two doors edged with mouldings, which are similar to those of the oven door, fig. 1, each door having the foliated ornament represented.

Above the doors the plate, fig. 2, projects, and this projecting portion of the

Horton and Martino's Design for Plates of a Cooking Stove.

plate is ornamented with ribs, which are bounded on the opposite sides by scrolled ornaments, each ornament surmounting a column formed partly of plain and partly of denticulated mouldings, one column being situated at each vertical edge of the plate.

The upper front plate, fig. 3, is edged above and below with a plain moulding, and has the scrolled and foliated ornament, represented with a central sprig, and the words United States on a scroll which forms a part of the ornament, there being on each end of the plate a sunk panel with the ornament shown.

The back plate, fig. 4, is edged with a plain moulding, and has the three scrolled and foliated ornaments clearly represented in the drawing.

We claim the combination of the ornamented figures in forms represented in and by the accompanying drawing, forming together an ornamental design for the plates of a cooking stove.

In testimony whereof, we have signed our names to this specification in the presence of two subscribing witnesses.

JAMES HORTON,
JOHN MARTINO.
